UNITED STATES PATENT OFFICE.

PAUL SCHILLING, OF MILWAUKEE, WISCONSIN, ASSIGNOR OF ONE-HALF TO
THEODORE D. SCHILLING, OF MILWAUKEE, WISCONSIN.

MATTRESS.

1,092,864.

Specification of Letters Patent. Patented Apr. 14, 1914.

Application filed December 3, 1910. Serial No. 595,381.

To all whom it may concern:

Be it known that I, PAUL SCHILLING, a citizen of the United States, residing in Milwaukee, in the county of Milwaukee and 5 State of Wisconsin, have invented new and useful Improvements in Mattresses, of which the following is a description, reference being had to the accompanying drawings, which are a part of this specification. 10 This invention relates to improvements in mattresses and more particularly to the manner of tacking or fastening the filling within the covering to said covering to hold it in position and also to preserve the box 15 edge effect of the mattress.

In fastening the filling to the covering of ordinary mattresses it is the custom to sew through the side edges of the cover and the filling and pass the needle through the upper 20 and lower portions of the cover at an angle and return the needle through the same upper and lower cover needle openings at different angles in order to have the loop of the thread or cord engage the material 25 within the cover and tack it to the side edges thereof. This sewing is usually done with the ordinary mattress needles which are triangular in cross section at both ends. In sewing, the needle cuts or breaks through 30 the cover fabric with the result that a great number of holes is formed in the fabric which not only mars the appearance of the article but provides entrance for vermin and 35 germs and is not conducive to sanitary conditions.

It is one of the objects of this invention to provide a mattress in which the before mentioned objectionable features are overcome by so positioning and arranging the sewing 40 openings that they will be covered and concealed from view by other necessary parts forming the mattress and also in part by other stitch lines.

With the above, and other objects in view, 45 the invention consists of the improved mattress and its parts and combinations as set forth in the claims, and all equivalents thereof.

In the accompanying drawing in which 50 the same reference characters indicate the same parts in all of the views: Figure 1 is a fragmentary top view of the improved mattress partly sewed and showing the manner of sewing, a part of the mattress being 55 broken away to show the interior construc-

tion; Fig. 2 is an edge view thereof also showing the manner of sewing, a portion of the mattress being broken away to show interior construction; Fig. 3 is a vertical sectional view thereof taken on line 3—3 of 60 Fig. 1; Fig. 4 is a fragmentary plan view of the completed mattress, a portion broken away to show interior looping engagement of thread with the filling material; Fig. 5 is an edge view thereof; Fig. 6 is a vertical 65 fragmentary sectional view of the completed mattress; Fig. 7 is a fragmentary top view of a modified form partly finished; Fig. 8 is a vertical sectional view thereof taken on line 8—8 of Fig. 7; and Fig. 9 is a similar 70 view taken on line 9—9 of Fig. 7 when finished.

Referring to the drawing the numeral 10 indicates the cover, 11 the cotton felt or other filling material, 12 the tufting strings 75 and 13 the tufts engaged thereby. In forming the improved mattress the cover is sewed and filled in the ordinary manner and the tufting strings 12 are passed back and forth through the cover and the filling 80 forming loops, the ends of which are loosely tied with slip knots 14. The side edges of the cover are now sewed to the filling by a line of stitching 15. In sewing the needle and the thread 16 are passed back and forth 85 and diagonally upwardly through the side edges of the cover and through the filling material and also through the upper portion of the cover. The needle and thread in passing through the upper portion of the cover 90 will form the apertures 17 and in the return stitches downwardly toward the side edge of the cover, the needle is returned through these same apertures so that the loops 18 of the thread will pass through the same apertures 95 and engage the filling material and bind said material to the side edge. Another line of stitches 19 also extending diagonally through the side edges and the upper portion of the mattress serves as an 100 additional means for securing the cover to the filling. These lines of stitches extend through the side edges of the mattress a slight distance above and below the lines of stitching 15 and pass through the upper 105 and lower portions of the cover at points in alignment with the apertures 17 so that the loops 20 of the thread or cord will cover the apertures 17 formed in sewing the lines of stitches 15. The tufts 13 are now placed 110

in the loops of the tufting strings and the slip knots 14 are forced down to tighten the strings and compress the mattress at these points. When sufficiently tightened the 5 strings are again knotted to securely fasten them in position thus completing the work and forming a mattress in which all of the sewing apertures are covered by the loops of the thread or cord.

10 In the modified form of mattress shown in Figs. 7, 8 and 9 the lines of stitching 21 from the side edges of the mattress are extended to and pass through the upper and lower portions of the cover at points close 15 to the tufting strings 12 forming apertures 22 through which the loops 23 are formed and return to engage the filling material 11. These apertures are covered by the tufts when engaged by the tufting strings and 20 the tufting strings are tightened in the same manner as before described.

From the foregoing description it will be seen that a mattress is provided in which the apertures formed in the cover in binding the filling and covering together are entirely covered from view and any foreign matter is prevented from entering therethrough.

What I claim as my invention is:

30 1. A mattress consisting of a cover provided with a filling material which has been sewed to the cover by a line of stitching which extends through the side edges of the cover and through and looped around the 35 filling material and entirely within the cover, said filling material engaging loops

having been formed outside of the cover by passing the needle and thread back and forth through apertures formed in the cover, and said cover being further stitched 40 to the filling material by another line of stitching which extends through one of the side edges and another portion of the cover and also through the filling material, said last mentioned stitch line having loops 45 which extend over and cover the cover apertures.

2. A mattress consisting of a cover provided with a filling material and having lines of stitching to connect the cover and the filling material together, said stitch lines being formed by sewing through the side edges and the top and bottom portions of the cover and through the filling material and returning the loops of the 50 thread through the needle apertures of the upper and lower portions of the cover to have the said loops engage the filling material and to be positioned entirely within the cover, and said mattress provided with 55 other lines of stitching which extend through the filling material and through the side edges and the top and bottom portions of the cover and loop over and cover the apertures of the said top and bottom 60 portions.

In testimony whereof, I affix my signature, in presence of two witnesses.

PAUL SCHILLING.
